UNITED STATES PATENT OFFICE

137,045

DESIGN FOR A TOWEL HOLDER OR SIMILAR ARTICLE

Edward W. Duffy, Boston, Mass.

Application October 7, 1943, Serial No. 111,289

Term of patent 14 years

To all whom it may concern:

Be it known that I, Edward W. Duffy, a citizen of the United States, residing at Boston, in the county of Suffolk and State of Massachusetts, have invented a new, original, and ornamental Design for a Towel Holder, or similar article, of which the following is a specification; reference being had to the accompanying drawing, forming a part thereof.

The towel shown in broken lines is for illustrative purposes, the essential feature of my design residing in the portion shown in full lines.

I claim:

The ornamental design for a towel holder or similar article, as shown and described.

EDWARD W. DUFFY.
